(57) **CLAIM**

The ornamental design for eyewear, as shown and described.

DESCRIPTION

FIG. 1 is a perspective view of eyewear showing the new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof, the left side being a mirror image thereof; and,

FIG. 7 is a left side elevation cross-section view thereof taken along line 7-7 in FIG. 2.

The broken lines immediately adjacent shaded areas represent bounds of and form no part of the claimed design. All other broken lines are directed to features of the eyewear that form no part of the claimed design.

1 Claim, 5 Drawing Sheets
